DOOR LOCK

Herman H. Kistner, Baltimore, Md., assignor to
 Kistner Lock & Appliance Company, a corporation of Maryland

Application January 29, 1936, Serial No. 61,382

5 Claims. (Cl. 70—370)

This invention relates to mortise locks and rim locks employing locks of the pin tumbler type usually called cylinder locks, and its object is to make them secure against forcible opening. In 5 this type of lock the bolt action is actuated by an arm on a rotating plug mounted in the cylinder lock which is received in a hole bored for it in the door and is screwed into the door lock casing from the outside and held therein by a set 10 screw or similar detent.

A serious defect of this type of lock is that the cylinder can be forcibly unscrewed from the outside by means of a Stillson wrench applied to its exterior flange, or heavy screw driver applied 15 to the key slot.

Another defect of locks of this general type, is that the pins that normally prevent the plugs from turning can be cut in two by drilling in from the outside on the line of intersection between 20 the exterior of the plug and the vertical axial plane of the cylinder and pins, and the plug freed so that it may be turned with a screw driver inserted in the screw slot.

These defects it is the object of the present invention to overcome in a simple and effective manner, and at no great increase in cost of the lock.

An illustrative embodiment of the invention is shown in the accompanying drawing, wherein

30 Fig. 1 is an outside view of a portion of a door at the lock, showing the door broken away to disclose the lock casing;

Figs. 2 and 3 are respectively a vertical cross-section thereof on the line 2—2 and a horizontal section on the line 3—3 in Fig. 1;

Fig. 4 is a cross-section on the line 4—4 in Fig. 2, looking in the direction of the arrows, showing a portion of the inside of the lock casing; and

Fig. 5 is a cross-sectional view to a larger scale 40 of a portion of the rim of the lock cylinder.

The lock illustrated in the drawing has a casing 11, secured in a mortise in the door 10 by means of screws 12 passing through the face flange 13, in the usual manner. The cylinders 45 14, 15, which carry the key actuated plug 16 and thumb latch 17 for operating the lock mechanism, screw into the flanged openings 18 in the casing and are secured there by means of a keeper, such as the yoke 19, the bifurcated ends 50 of which engage in one or the other of the grooves 20. The yoke is slidable axially to clamp the cylinders and is held in clamping position by means of a screw 21, which passes through the face flange 13 and is inaccessible when the door 55 is shut.

The sliding bolt 25 and its locking mechanism 26 are actuated by arms 27 on the inner ends of the plug 16 and thumb latch 17, respectively, as is common in locks of this type.

The outer cylinder 14, which carries the key 5 operated plug 16, is fitted with a loose flange 30 made of case hardened steel or hard bronze, secured in place by an expanding ring 31 arranged in alining grooves in the flange and cylinder respectively, the groove in the cylinder being deep 10 enough to receive the full thickness of the ring in compressed position so as to permit the flange 15 to be slipped over it into place, as shown in Fig. 5. When the ring expands into the groove in the flange, the latter is locked on the cylinder and cannot be removed without breaking it. Between the flange and the door is the usual loose ferrule 32, to fill the gap between the flange and face of the door on doors of less than maximum thickness. 20

The first two locking pins 33 and their drivers 34 are made of hardened steel to prevent drilling through them, the construction of the remaining locking pins 35 and drivers 36, and the tumbler springs 37 being the same as usual in this type of 25 lock.

On the inner end of the outer cylinder 14, between it and the adjacent arm 27 carried by the plug 16, is secured an adjustable retaining sector 30 or guard 40, which projects beyond the periphery of the cylinder and engages behind the flange 41 on the lock casing surrounding the threaded opening for the cylinder, so as to prevent unscrewing the latter, as shown in Fig. 4. This sector is held in place by two countersunk screws 42, 43, and is provided with a short slot 44 instead of a circular hole for the screw 43 to enable it to be swung inwards a little when the screws are loosened to permit the cylinder to be screwed 35 in and out of the casing. These screws 42, 43, are readily reached with a screw driver from the inside side of the door through the opening for the thumb latch cylinder 15 to tighten and loosen them and manipulate the sector when the outer 40 cylinder 14 needs to be changed. 45

The loose flange 30 and guard sector 40 prevent forcible unscrewing of the cylinder 14 by a Stillson wrench, cold chisel or other implement readily applied to the outer end of the cylinder 50 or inserted in the key slot, and neither the flange nor the guard can be removed by any force that can be applied while the cylinder is in the casing.

I have described what I consider to be the preferred form of my invention, but the invention 55

is not restricted to the construction shown in the drawing.

What I claim is as follows:

5. In a door lock having means engaging the periphery of a cylinder lock for retaining the cylinder from being unscrewed from the lock casing when the door is closed, the combination of a cylinder lock, a pivoted guard means carried by the cylinder adjacent to its inner end for engaging the inner face of the door lock casing to prevent forcible unscrewing of the cylinder, and means for fixedly securing said guard means in adjusted position to the end face of the cylinder, said means being adjusted from within after the cylinder is installed in the lock casing, where-
10 by it cannot be removed except from within.
15. A cylinder for a pin tumbler lock adapted to screw into a door lock casing, said cylinder having a plug with an operating arm at its inner end, and guard means arranged between said operating arm in its normal position and the adjacent end of said cylinder and adapted to be fixedly secured thereto with a portion projecting radially beyond the periphery of the cylinder to engage the inner face of the lock casing and prevent unscrewing of said cylinder when assembled therewith.
20. A cylinder for a pin tumbler lock having a sector shaped guard plate with a slot secured on its inner end by means permitting outward adjustment thereof when in place, said means comprising two fixed screws one of which passes through the slot in the guard plate.
25. In a door lock having means for engaging

the periphery of a cylinder lock for retaining the cylinder from being unscrewed from the lock casing when the door is closed, the combination of a cylinder lock, a pivoted guard means carried by the cylinder adjacent to its inner end for engaging the inner face of the door lock casing to prevent forcible unscrewing of the cylinder, and means for fixedly securing said guard means in adjusted position to the end face of the cylinder, said means being adjusted from within after the cylinder is installed in the lock casing, where-
10 by it cannot be removed except from within.

5. A cylinder casing for a pin tumbler lock having a groove on its outer surface adapted to be engaged by a keeper for retaining it in a door lock casing, and a sector shaped guard carried by said cylinder casing adjacent its inner end between it and the path of movement of the bolt actuating cam and projectable into the door lock casing to engage the inner wall thereof for preventing forcible removal of the cylinder therefrom, said guard having securing means adjustable to hold it out of operative position during the operation of assembling the lock and in operative position after the cylinder is installed in the door lock casing, said means being adjustable from within only when assembled in the door lock casing.

HERMAN H. KISTNER.
